UNITED STATES PATENT OFFICE.

AUGUSTUS G. CHRISTMAN, OF READING, PENNSYLVANIA.

DESIGN FOR AN AGITATOR FOR WASHING-MACHINES.

SPECIFICATION forming part of Design No. 31,154, dated July 4, 1899.

Application filed June 7, 1899. Serial No. 719,720. Term of patent 14 years.

To all whom it may concern:

Be it known that I, AUGUSTUS G. CHRISTMAN, a citizen of the United States, residing at Reading, in the county of Berks and State of Pennsylvania, have invented and produced a new and original Design for an Agitator for Washing-Machines; and I do hereby declare the following to be a full, clear, and exact description of the same, reference being had to the accompanying drawings, forming a part thereof.

This is a design for an agitator for washing-machines.

Figure 1 is a plan view of the design, and Fig. 2 is a cross-sectional view on line $x-x$ of Fig. 1.

The leading feature of my design is the approximately quadrangular frame having Y -shaped cross-arms therein.

The frame A, as shown in Fig. 1, is approximately quadrangular, having its sides A' curved slightly outward and formed with a circular opening a in each of the corners

thereof. An opening a' slightly smaller in diameter than the corner openings is located on each side midway between two corners. Cross-arms B run diagonally across the inside of the frame A, and their ends terminate in forked arms b, which join the sides A' of the frame and form an approximate letter Y . A series of alternately-arranged long and short rubbers C depend from the frame A. A rod D projects upwardly from the center of the frame.

Having thus fully described my invention, what I claim, and desire to secure by Letters Patent, is--

The design for an agitator for washing-machines as herein shown and described.

In testimony whereof I affix my signature in presence of two witnesses.

AUGUSTUS G. CHRISTMAN.
